MEANS FOR REMOVING BROKEN STUD BOLTS

Filed June 17, 1924

FIG. 1.

FIG. 2.

FIG. 3.

Inventor
Willie J. Murphree.

By Clarence O'Brien.
Attorney

Patented July 28, 1925.

UNITED STATES PATENT OFFICE.

WILLIE J. MURPHREE, OF EL CENTRO, CALIFORNIA.

MEANS FOR REMOVING BROKEN STUD BOLTS.

Application filed June 17, 1924. Serial No. 720,627.

To all whom it may concern:

Be it known that I, WILLIE J. MURPHREE, a citizen of the United States, residing at El Centro, in the county of Imperial and 5 State of California, have invented certain new and useful Improvements in a Means for Removing Broken Stud Bolts, of which the following is a specification.

This invention relates to new and useful 10 improvements in a means for removing broken stud bolts and has for its principal object to provide a means which will efficiently and positively remove a broken stud bolt.

15 Another important object of the invention is to provide a means for removing broken stud bolts and is especially adapted for use in conjunction with the removal of broken stud bolts from a cylinder block.

20 A still further object of the invention is to provide a means of the above mentioned character, which is simple in construction, inexpensive, strong and durable and furthermore adapted for the purposes for which it 25 is designated.

A still further object is to provide a means for removing broken stud bolts of the above mentioned character which may be readily and easily used and will further save considerable time in extracting broken stud bolts.

Other objects and advantages of this invention will become apparent during the course of the following description.

35 In the accompanying drawing forming a part of this specification and in which like numerals designate like parts throughout the same:

Figure 1 is a detail perspective view of my 40 improved tool;

Fig. 2 is a view partly in section and partly in side elevation, showing the manner in which the tool is used in forming the grooves in the inner wall of a broken stud bolt 45 which is threaded in a cylinder block; and

Fig. 3 is a bottom plan view of my improved tool.

In the drawing wherein for the purpose of illustration is shown the preferred embodiment of my invention, the numeral 1 designates generally my improved tool and the same comprises the cylindrical shank portion, the lower portion of which is provided with longitudinally extending spaced 50 grooves 3 whereby the longitudinal ribs 4 are formed thereby. The bottom of the

tool is drilled to form the substantially concaved portion 5 whereby cutting edges 6 are formed on the lower edges of the longitudinally extending ribs 4, the purpose of which 60 will be hereinafter more fully described.

The upper end of the shank portion 2 of the tool 1 is provided with the square head 7 whereby a means is provided for the reception of a wrench or other similar tool to 65 facilitate the rotation of the tool when removing a broken stud bolt.

In removing broken stud bolts, the stud bolt A which is threaded in the cylinder block B in the manner well known in the 70 art has an opening drilled in the top thereof, it being understood of course that the hole or opening 8 is of a diameter slightly less than the diameter of the bolt extracting tool. The tool 1 is then placed over the 75 opening 8 so as to have the cutting edges 6 resting on the top of the bolt A. The tool is then struck with a hammer on the head 7 thereof so that the cutting edges 6 will cut into the upper portion of the stud bolt 80 and form a plurality of vertical spaced grooves in the inner wall of the broken stud bolt simultaneously causing the ribs 4 on the lower edges of which are formed the cutting edges 6 to be received in the 85 longitudinal grooves formed by the cutting edges. The portions of the stud bolts A which are cut away in forming the grooves in the inner wall of the bolt are illustrated at 9 in Fig. 2 of the drawing.

After the tool has been driven down into the stud bolt for a suitable distance so that the rib 4 will be seated in the longitudinal grooves in the broken stud bolt the wrench or other suitable tool is placed in engagement with the square head 7 on the upper 90 end of the tool and by turning the tool in the proper direction, the coating ribs and grooves will cause the broken stud bolt to be entirely removed from threaded engagement with its support.

It will thus be seen from the foregoing description, that a simple and efficient means has been provided whereby broken stud bolts may be readily and easily removed 105 without the loss of time or labor. It is of course to be understood that the tool used in removing broken stud bolts is constructed of any suitable material, preferably hardened tool steel. Further a tool of this 110 character may be employed in connection with either left or right threaded bolts.

While I have shown the preferred embodiment of my invention, it is to be understood that various changes in the size, shape and arrangement of parts may be resorted to without departing from the spirit of the invention and the scope of the appended claim.

Having thus described the invention, what I claim is:—

A tool for removing broken stud bolts, 10 the latter having an opening formed in the top thereof, said tool comprising a shank portion of greater diameter than the diameter of the opening, longitudinally spaced ribs on the outer portion of the shank, the

bottom of the tool being substantially concaved forming cutting edges on the lower edges of the ribs for engaging the end of the stud bolt to be removed adjacent its opening whereby when the tool is driven into the opening vertically spaced grooves 20 are formed in the inner wall of the bolt to receive the ribs, and a tool-engaging head on the upper end of the shank for turning the same and removing the stud bolt.

In testimony whereof I affix my signature.

WILLIE J. MURPHREE.
